Howard E. Van Ness,

By his Atty., J. W. Richard,

UNITED STATES PATENT OFFICE.

HOWARD E. VAN NESS, OF LITTLE FALLS, NEW JERSEY.

RAIL-FASTENER.

1,163,186.

Specification of Letters Patent.

Patented Dec. 7, 1915.

Application filed July 7, 1915. Serial No. 38,409.

To all whom it may concern:

Be it known that I, HOWARD E. VAN NESS, a citizen of the United States, residing in Little Falls, in the county of Passaic and State of New Jersey, have invented certain new and useful Improvements in Rail-Fasteners, of which the following is a specification.

This invention relates to rail fasteners, and one of the main objects of the invention is to provide a rail fastener which is held in place by clamping members capable of withstanding great strains, yet sufficiently resiliant to be practically immune to fracture.

Still another object of the invention is to provide a clamping means for rail fasteners which are sufficiently yieldable to prevent destruction by fracture, and thus, although they may be distorted, will never be entirely deprived of their clamping effect.

These and other features, capabilities and advantages of the invention will appear from the subjoined detail description of specific embodiments thereof illustrated in the accompanying drawings, in which—

Figure 1 is a transverse section of a rail resting upon a tie-plate the whole secured to a wooden tie with the means forming the present improvement. Fig. 2 is a fragmental view, partly in section, showing part of the tie in end elevation. Fig. 3 is a fragmental plan showing part of the tie-plate. Figs. 4 and 5 are side and end elevations respectively of the clamping means; Fig. 6 is a bottom plan view of the same; and Fig. 7 is a perspective of the clamping means. Fig. 8 is a perspective view of one of the dogs or clips co-operating with the clamping means. Fig. 9 is an elevation illustrating in full lines the position of the clamping means before being secured in clamping position, and in dotted lines the position of the clamping means after being secured in clamping position. Fig. 10 is a transverse section of a rail secured to an I-beam sleeper by the means forming the present improvement; and Fig. 11 is a fragmental elevation of the same showing the I-beam sleeper in section. Fig. 12 is a fragmental plan of the upper portion of the I-beam sleeper.

In the embodiment shown in Figs. 1, 2 and 3, there is provided a rail R disposed on the bed-plate or tie-plate 15 secured to a wooden tie 16 by the clamping means forming the subject-matter of the present invention.

Preferably with the present clamping means, the tie-plates are provided with key-shaped apertures 17, an aperture on each side of the base flange 18 of the rail R, with an elongated narrow portion 19 adjacent to the rail, and an enlargement 20 at the remote end of such aperture. Disposed in the narrow elongated portion 19 of the aperture 17, there is provided a dog 21 having two fingers 22 extending in the same direction, the inner faces 23 of which are inclined away from one another as they extend from the intermediate portion 24 of the dog. The lower surfaces 25 of the tie-plate 15 adjacent to the inner ends of the apertures 17 are beveled. Thus, when a dog 21 is secured in place, the inclined faces 23 of the fingers 22 will engage the usual inclined upper surface of the base flange 18 of the rail R and the beveled portion 25 of the tie-plate 15. Through the enlarged portion 20 of the aperture 17 extends a suitable securing means such as the screw 26. The securing means or screw 26 engages the clamping means forming the main feature of the present improvement and presses the same against the dog 21. The clamping means comprises essentially a sheet metal plate C having an upper curved portion 27, a lower straight portion 28, and an intermediate connecting portion 29, the upper portion 27 being considerably longer and broader than the lower portion 28. In the upper portion 27 there is formed an opening 30 to receive the screw 26. When the securing means, in the present instance the screw 26, is disposed in the opening 30, the free edge of the lower portion 28 is adapted to abut against such screw 26 to perch thereagainst while the upper portion 27 is being expanded. To form a suitable perch for the screw 26, the free end of the lower portion 28 is provided with a recess 31. In use, the clamping means has its lower portion 28 disposed against the wooden tie 16 in the aperture 17, its intermediate portion 29 disposed against the dog 21, and the free end of the upper portion 27 resting on the upper surface of the tie-plate 15. Thereupon, when the screw 26 is driven into the wooden tie 16, and its head 32 engages the upper portion 27, the clamping means C will expand, the upper portion 27 practically straightening out, as shown in dotted lines in Fig. 9, and its intermediate portion 29 being extended or pressed tightly against the dog 21.

In the embodiment shown in Figs. 10, 11 and 12, the rail R is secured directly to an I-beam sleeper 33, in which case there are provided two apertures 34 in the upper cross-piece 41 of the I-beam sleeper and adjacent to each side of the base flange of the rail R, preferably one on either side of the web 42 of the I-beam sleeper, these apertures 34 being formed similar to the apertures 17 of the tie-plate 15 and having elongated narrow portions 35 adjacent to the base flange 18 and enlarged portions 36 at the ends of the apertures 34 remote from the flange 18. In use, somewhat different than 15 with the construction shown in Figs. 1, 2 and 3, a dog 37 is disposed in the elongated narrow portion 35 of each aperture 34, the dog having two fingers 38, 38, the inner surface 39 of the upper finger being inclined to correspond with and engage the inclined upper surface of the base flange 18 of the rail R, while the inner surface 40 of the lower finger is not necessarily inclined, but may be straight, as shown, to engage the straight lower surface of the cross-piece 41 of the I-beam sleeper 33. Through the enlarged portions 36, bolts 43 extend. Clamping plates C, such as illustrated in Figs. 4 to 6 inclusive, are here used, the bolts extending through the openings 30 of the upper portions 27 and engaging the recesses 31, while the intermediate connecting portions 29 engage the dogs 37, and when the nuts 44 of the bolts 43 are driven tight, they will 35 engage the upper portions 27 of the clamping plates C and straighten out such upper portions and press the connecting portions 29 against the dogs 37. The heads of the bolts 43, as shown in Figs. 10 and 11, engage the lower surfaces of the cross-piece 41 of the I-beam sleeper 33.

It is obvious that various changes and modifications may be made to the details of construction without departing from the 45 spirit of the invention.

I claim:

1. In combination with the plate portion of a rail bed, of a rail fastener for a rail having a base flange, anchoring means engaging said plate portion and said base flange, and extensible clamping means for being extended into engagement with said anchoring means and thereby lock the same in place.

2. In combination with the plate portion of a rail bed, of a rail fastener for a rail having a base flange, there being apertures in said plate portion adjacent to said base flange, anchoring means disposed in the apertures adjacent to said base flange and engaging the same, and yieldable clamping means for locking said anchoring means in place.

3. In combination with the plate portion of a rail bed, of a rail fastener for a rail

having a base flange, there being apertures in said plate portion adjacent to said base flange, anchoring means disposed in the apertures adjacent to said base flange, fingers on said anchoring means, one engaging the upper surface of the base flange and the other engaging the lower surface of the plate portion adjacent to said base flange, and yieldable clamping means for locking the said anchoring means in place.

4. In combination with the plate portion of a rail bed, of a rail fastener for a rail having a base flange, there being apertures in said plate portion adjacent to said base flange, anchoring means disposed in the apertures adjacent to said base flange, fingers on said anchoring means, one engaging the upper surface of the base flange and the other engaging the lower surface of the plate portion adjacent to said base flange, the inner surface of the finger adjacent to the base flange being inclined to correspond with and engage the inclined upper surface of the base flange, and yieldable clamping means for locking the said anchoring means in place.

5. In combination with the plate portion of a rail bed, of a rail fastener for a rail having a base flange, there being apertures in said plate portion adjacent to said base flange, anchoring means disposed in the apertures adjacent to said base flange, fingers on said anchoring means, one engaging the upper surface of the base flange and the other engaging the lower surface of the plate portion adjacent to said base flange, the lower surface of the plate portion adjacent to the base flange being inclined, the inner surface of the fingers being inclined one to correspond with and engage the upper surface of the base flange and the other to correspond with and engage the lower inclined surface of the plate portion, and yieldable clamping means for locking the said anchoring means in place.

6. In combination with the plate portion of a rail bed, of a rail fastener for a rail having a base flange, there being apertures in said plate portion adjacent to said base flange, dogs in said apertures adjacent to said base flange to engage the same, clamping plates, and securing means for pressing said clamping plates into engagement with and securely anchoring said dogs in place.

7. In combination with the plate portion of a rail bed, of a rail fastener for a rail having a base flange, there being apertures in said plate portion adjacent to said base flange, dogs in said apertures adjacent to said base flange to engage the same, clamping plates, and securing means extending through the other ends of said apertures and pressing said clamping plates into engagement with and securely anchoring said dogs in place.

8. In combination with the plate portion of a rail bed, of a rail fastener for a rail having a base flange, there being apertures in said plate portion adjacent to said base flange, dogs in said apertures adjacent to said base flange to engage the same, clamping plates, and screws extending through the other ends of said apertures and pressing said clamping plates into engagement with and securely anchoring said dogs in place.

9. In combination with the plate portion of a rail bed, of a rail fastener for a rail having a base flange, there being apertures in said plate portion having elongated narrow portions adjacent to said base flange and enlarged portions at the ends of said apertures remote from said base flange, dogs in said apertures adjacent to said base flange to engage the same, clamping plates, and securing means for pressing said clamping plates into engagement with and securely anchoring said dogs in place.

10. In combination with the plate portion of a rail bed, of a rail fastener for a rail having a base flange, there being apertures in said plate portion adjacent to said base flange, dogs in said apertures adjacent to said base flange to engage the same, clamping plates each having an upper portion, a lower portion, and an intermediate connecting portion, there being an opening in said upper portion, and securing means extending through the openings of said upper portions and through the ends of said apertures to expand said plates so that their intermediate connecting portions will engage said dogs and securely anchor them in place.

11. In combination with the plate portion of a rail bed, of a rail fastener for a rail having a base flange, there being apertures in said plate portion adjacent to said base flange, dogs in said apertures adjacent to said base flange to engage the same, clamping plates each having a curved upper portion, a straight lower portion, and an intermediate connecting portion, there being an opening in said upper portion, and securing means extending through the openings of said upper portions and through the other ends of said apertures to straighten out said plates so that their intermediate connecting portions will engage said dogs and securely anchor them in place.

12. In combination with the plate portion of a rail bed, of a rail fastener for a rail having a base flange, there being apertures in said plate portion adjacent to said base flange, dogs in said apertures adjacent to said base flange to engage the same, clamping plates each having an elongated curved upper portion, a short straight lower portion, and an intermediate connecting upper portion, there being an opening in said upper portion, and securing means ex-

tending through the openings of said upper portions and through the other ends of said apertures and pressing down on said upper portions, the lower straight portions engaging said plate portion and also said securing means so that when said upper portions are pressed down, the lower portions being fixed, the intermediate connecting portions will extend outward and engage said dogs.

13. In combination with the plate portion of a rail bed, of a rail fastener for a rail having a base flange, there being apertures in said plate portion adjacent to said base flange, dogs in said apertures adjacent to said base flange to engage the same, clamping plates each having an elongated curved upper portion, a narrow and short lower portion disposed in an aperture, and an intermediate connecting portion connecting said lower and upper portions, there being an opening in said upper portion, and securing means extending through the openings of said upper portions and through the other ends of said apertures and pressing down on said upper portions, the lower straight portions engaging said plate portion and also said securing means so that when said upper portions are pressed down, the lower portions being fixed, the intermediate connecting portions will extend outward and engage said dogs.

14. In combination with the plate portion of a rail bed, of a rail fastener for a rail having a base flange, there being apertures in said plate portion adjacent to said base flange, dogs in said apertures adjacent to said base flange to engage the same, clamping plates each having an elongated curved upper portion, a short straight lower portion, and an intermediate connecting portion, there being an opening in said upper portion, and securing means extending through the openings of said upper portions and through the other ends of said apertures and pressing down on said upper portions, the lower portions having curved recesses to serve as seats for said securing means, the lower straight portions engaging said plate portion and also said securing means so that when said upper portions are pressed down, the lower portions being fixed, the intermediate connecting portions will extend outward and engage said dogs.

15. In combination with the plate portion of a rail bed, of a rail fastener for a rail having a base flange, there being apertures in said plate portion adjacent to said base flange, dogs in said apertures adjacent to said base flange to engage the same, clamping plates each having an elongated curved upper portion, a short straight lower portion, and an intermediate connecting portion, there being an opening in said upper portion, and screws extending through the

openings of said upper portions, heads on said screws pressing down on said upper portions, the lower straight portions engaging said plate portion and also said screws so that when said upper portions are pressed down, the lower portions being fixed, the intermediate connecting portions will extend outward and engage said dogs.

16. As an article of manufacture, a clamping plate for a rail fastener having an upper portion, a lower portion, and an intermediate connecting portion, there being an opening in said upper portion, one edge of said opening being in alinement with the free edge of said lower portion so that the free edge of said lower portion will be engaged by the securing means that extend through said opening to clamp said upper and lower portions together while said intermediate connecting portion is extended into engagement with the anchoring means of the rail fastener.

17. As an article of manufacture, a clamping plate for a rail fastener having a curved upper portion, a straight lower portion, and an intermediate connecting portion, there being an opening in said upper portion, the free edge of said lower portion being in alinement with one edge of said opening so that said free edge will be engaged by the securing means that pass through said opening to straighten out said curved upper portion thereby to extend said intermediate portion into engagement with the anchoring means of the rail fastener.

18. As an article of manufacture, a clamping plate for a rail fastener having an elongated curved upper portion, a narrow and short lower portion, and an intermediate connecting portion connecting said upper and lower portions, there being an opening in said upper portion, the free edge of said lower portion being in alinement with one edge of said opening so that such free edge will be engaged by the securing means passing through said opening to straighten out said curved upper portion thereby to extend said intermediate connecting portion into engagement with the anchoring means of the rail fastener.

19. As an article of manufacture, a clamping plate for a rail fastener having an expandible portion, and an anchoring means

engaging portion adapted to be extended into engagement with the anchoring means 55 of the rail fastener.

20. In combination with the plate portion of a rail bed, of a rail fastener for a rail having a base flange, dogs engaging said plate portion and said base flange for locking the same together, clamping plates each having a curved upper portion, a straight lower portion, and an intermediate connecting portion, and securing means for pressing the curved upper portions of the clamping plates toward the straight lower portions whereby the upper portions will be straightened out and the intermediate connecting portions extended into engagement with the dogs and thereby the dogs securely 70 anchored in place.

21. In combination with the plate portion of a rail bed, of a rail fastener for a rail having a base flange, anchoring means engaging said plate portion and said base 75 flange for locking the same together, clamping plates each having an elongated curved upper portion, a short straight lower portion, and an intermediate connecting portion, and securing means for pressing said 80 curved upper portions so that said intermediate connecting portions will extend into engagement with said anchoring means to securely anchor them in place.

22. In combination with the plate portion 85 of a rail bed, of a rail fastener for a rail having a base flange, anchoring means engaging said plate portion and said base flange for locking the same together, resilient clamping plates, and securing means for pressing said clamping plates into engagement with and securely anchoring said anchoring means in place.

23. In combination with the plate portion 95 of a rail bed, of a rail fastener for a rail having a base flange, dogs engaging said plate portion and said base flange for locking the same together, resilient clamping plates, and securing means for pressing said 100 clamping plates into engagement with and securely anchoring said dogs in place.
